CLAIM

The ornamental design for a necklace, as shown and described.

DESCRIPTION

FIG. 1 is a front elevation view of a necklace showing my new design.

FIG. 2 is an enlarged view of the portion highlighted in FIG. 1.

FIG. 3 is a rear elevation view of the necklace of FIG. 1.

FIG. 4 is an enlarged view of the portion highlighted in FIG. 3.

FIG. 5 is a left side elevation view of the necklace of FIG. 1.

FIG. 6 is an enlarged view of the portion highlighted in FIG. 5.

FIG. 7 is a right side elevation view of the necklace of FIG. 1.

FIG. 8 is an enlarged view of the portion highlighted in FIG. 7.

FIG. 9 is a top plan view of the necklace of FIG. 1.

FIG. 10 is a bottom plan view of the necklace of FIG. 1.

FIG. 11 is a top perspective view of the necklace of FIG. 1.

FIG. 12 is an enlarged view of the portion highlighted in FIG. 11.

FIG. 13 is another front view of the necklace of FIG. 1; and, FIG. 14 is an enlarged view of the portion highlighted in FIG. 13.

The broken lines depicted throughout the drawings represent environmental structure and do not form part of the claimed design.

1 Claim, 14 Drawing Sheets
